JAMES S. REID, OF SHAKER HEIGHTS, OHIO, ASSIGNOR TO THE REID PRODUCTS COMPANY, OF CLEVELAND, OHIO, A CORPORATION OF OHIO

GLASS RUN CHANNEL STRUCTURE

Application filed August 6, 1931. Serial No. 555,518.

The invention of this application relates to glass run channel structures for use with the windows of motor vehicles and the like.

The object of the present invention is to combine finishing strip and glass run channel features, wherein the channel structure includes an outer main channel adapted to fit snugly within a window groove and preferably made of a non-metallic material, such as paper to prevent chattering and other noise, said channel having polished finishing strips applied to the upper edges of each of the side flanges thereof. Such channel structure also includes a pair of lip pad strips of spring metal or the like projecting inward from the channel side flanges and secured thereto by lugs integral with said lip pad strips and extending through slots in said channel side flanges. Suitable cushioning means is, of course, provided for the glass-engaging portions of said lip pad strips and for the inner surface of the bottom of the main channel.

Another feature of the invention is one wherein the main outer channel, having the finishing strips, is made of two separate channel portions, each including a side flange and a base flange and each side flange provided with a lip pad projecting inwardly therefrom, the two half-channel portions being secured in place by a separate base member forced down between the side flanges of the two channel portions against the base flanges. This base member is preferably provided with a suitable cushioning pad for engaging the edge of the glass.

Another feature of the invention is an arrangement of the base portion of a unitary outer or main channel, of paper or the like, bulged upward in such a way as to form a cushioning yielding base for engagement with the edge of the glass and of a construction such that its depression causes the inner or base edges of the side flanges to be forced out against the sides and into the corners of the window groove.

The invention is well set forth in the following description, drawings and claims.

Referring to the drawings, Fig. 1 is a view, partly in section and partly in eleva-

tion, showing the channel structure applied to a portion of the window frame; Fig. 2 is an enlarged view of a portion of the lip pad members removed from the main channel; Fig. 3 is an enlarged view of the main channel with the lip pad members removed; Fig. 4 shows a modified form wherein the main channel is made up of two side channel portions and a separate base; and Fig. 5 is a similar view showing still another modified form wherein the main channel is of substantially U-shaped form with the base bulged upward to provide a yielding glass edge-engaging portion.

Referring to the drawings, 1 represents the frame of the window provided with a window groove, indicated at 2. Within this window groove the channel structures herein described are applied.

In the channel structure shown in Figs. 1, 2 and 3, the outer main channel of non-metallic material, such as stiff waterproof paper, comprises a base 3, and side flanges 4. Each of these side flanges is provided along its outer edge with a finishing strip comprising the two side portions 5 and 6 and the top loop or cross portion 7. Each of the side flanges is further provided with longitudinal slots 8, spaced longitudinally therealong a short distance above the base, as shown in Fig. 3.

Engaging the side flanges are the lip pad strips, each of which comprises a vertical longitudinally extending strip portion 9 and an inwardly diagonally extending lip portion 10, beaded over as at 11. At the lower edge of the main strip portion 9 are suitable tongues or lugs 12, like in number to and spaced to correspond with the slots 8 in the side flanges of the main channel. The lip pad strips have their tongues 12 inserted outward through the slots 8 and bent downward on the outside of the side flanges of the main channel to hold the lip pad strips in place.

Each of the portions 10 of the lip pad strips may be covered by an inner covering 13 of rubber and an outer felt layer 14, a suitable bead or thickened rubber portion 15 being provided around the outer edge.

From the foregoing, it will be seen that the

spreading tendency of the glass causes the lip pad strips to bear at substantially the points marked 16 against the inner faces of the side flanges of the main channel, causing a pull inward on the tongue, which through the downwardly bent portions on the outside hold and resist this movement, resulting in the lip pad strips having a yielding action upon the glass. A channel structure of this type is noiseless and readily adapts itself to the window groove and fulfills all the desired window channel requirements.

5 In the modification shown in Fig. 4, the main channel is made up of two separate side 15 channel portions, including side flanges 17 and base flanges 18. Forced down between the side flanges and engaging the base flanges 18 is a bottom strip 19 provided with a suitable pad 20 on its upper surface. When the 20 bottom strip is in place the two channel portions are held in proper position in the window groove. In this arrangement the same lip pad strips as set forth in Figs. 1 to 3 are employed and need no further description.

25 In the modification shown in Fig. 5, the main channel including side flanges 21 and 22 is provided with a curved base member 23, which may be a separate piece, as in Fig. 4, or may be integral with the side flanges.

30 Having described my invention, I claim:

1. A glass run channel structure, comprising a non-metallic generally U-shaped channel member having side flanges and a base portion, finishing strips at the outer edges of 35 said flanges, and a pair of glass-engaging lip pad strips, one for each of said side flanges, each of said lip pad strips comprising a main strip portion engaging the inner surface of one of said side flanges, a glass-engaging padded lip portion secured to said main strip portion and means integral with said main strip portion for securing the same to one of 40 said side flanges.

45 2. A glass run channel structure as set forth in claim 1, characterized in that the securing means for said lip pad strips comprise tongues integral with the main strip portions of said strips and characterized further in that the side flanges of said channel member 50 are provided with slots to receive said tongues.

In testimony whereof I hereby affix my signature.

JAMES S. REID.
